UNITED STATES PATENT OFFICE.

ETHAN I. DODDS, OF AVALON, PENNSYLVANIA, ASSIGNOR TO PRESSED STEEL CAR COMPANY, OF PITTSBURG, PENNSYLVANIA, A CORPORATION OF NEW JERSEY.

TANK-CAR FRAME AND METHOD OF MAKING THE FRAME.

SPECIFICATION forming part of Letters Patent No. 770,713, dated September 20, 1904.

Application filed January 25, 1904. Serial No. 190,421. (No model.)

To all whom it may concern:

Be it known that I, ETHAN I. DODDS, of Avalon, Allegheny county, Pennsylvania, have invented a new and useful Tank-Car Frame and 5 Method of Making the Frame, of which the following is a full, clear, and exact description, reference being had to the accompanying drawings, forming part of this specification, in which—

10 Figure 1 shows in vertical cross-section the frame of a tank-car constructed in accordance with my invention and showing the body bolster of the car. Fig. 2 is a similar section on a different plane, showing one of the flying 15 transoms. Fig. 3 shows the manner in which a flanged beam, either a channel-beam or an I-beam, is cut for the purpose of forming the parts of the form shown in Figs. 1 and 2. Fig. 4 is a vertical section on the line IV IV 20 of Fig. 1, and Fig. 5 is a vertical section on the line V V of Fig. 2. Fig. 6 shows a modification.

25 My invention enables me to make body-bolsters and transoms of tank-cars and the tank-supports thereof from steel beams without any waste or with the least possible waste of material. I thus produce a car-frame at minimum cost, and as I preserve the original flanges on the sections of which it is formed 30 it is of maximum strength.

In the manufacture of the parts of the car I take a flanged beam, (shown in Fig. 3,) which may be either a channel-beam or an I-beam, but is of the length desired for the width of 35 the car, and divide it by a cut *b b*, extending longitudinally through the web and at an inclination from the middle toward the ends, the cut being preferably in a continuous curve, as shown in Fig. 3. This produces 40 two sections 2 3, the section 2 having a cut edge of concave curvature and the section 3 having a cut edge of convex curvature. The cut is produced by a press which divides it simultaneously from end to end. The section

45 3 is then cut at the middle portion on a curved line *c c*, the curvature of which is preferably adapted to fit the tank 4 of the car and to provide a recess therefor. A number of such

sections 3 are then adapted to be applied to the car-frame directly above the bolsters and 50 transoms as a tank-cradle, as shown in Figs. 1 and 2, the middle curved portion being reinforced, if desired, by angle-pieces 5 5. If the contour of the cut *c c* does not fit exactly 55 the contour of the tank which is resting thereon, an exact contour may be secured by proper placing of the reinforcing-angles 5 5. The other section, 2, is divided at the middle by a transverse cut *d d*, thus constituting two sections 2 2', which are applied in the building 60 up of a flying transom, as at 2^a in Fig. 2, or to the building up of a body-bolster, as at 2^b in Fig. 1. The upper margins of the parts thus constituted have the original flanges of 65 the beam, and the lower margins, if desired, may be reinforced by angles 6, as shown in Fig. 1.

When the parts are assembled as above described, they form a combined tank-cradle and bolster or transom of novel construction. 70 The tank-cradle is directly above the transom or bolster and constitutes a tension member therefor. I desire to cover such construction whether the parts be formed according to the method above described or whether they be 75 formed of plates and reinforcing-angles assembled by riveting.

Those skilled in the art will be able to modify my invention to suit the particular pattern of car to which the parts are to be 80 applied, since

What I claim is—

1. The method of making a tank-support and bolster or transom members from a single beam-section, which consists in dividing 85 a flanged beam longitudinally through its web by a cut extending in a bias direction relatively to the flanges from the middle of the beam-section toward the end, dividing transversely one of the parts thus formed and 90 cutting a tank-supporting recess in the other part; substantially as described.

2. The method of making a tank-support and bolster or transom members from a single beam-section, which consists in dividing 95 a flanged beam longitudinally through its web

by a cut extending in a bias direction relatively to the flanges from the middle of the beam-section toward the end, dividing transversely one of the parts thus formed and cutting a tank-supporting recess in the other part, said bias cut being formed in a curve extending from end to end of the beam-section; substantially as described.

3. A combined tank-cradle and bolster or transom, comprising a cradle - supporting member, extending substantially to the sides of the car set over the bolster or transom and constituting a tension member therefor; substantially as described.

15 4. A combined tank-cradle and car bolster

or transom, which consists of a cradle-section having an integral flange along one edge, and a bolster or transom likewise having an integral flange along one edge, said flanges being placed adjacent to one another, the cradle-section being set over the bolster or transom section and forming a tension member therefor; substantially as described. 20

In testimony whereof I have hereunto set my hand.

ETHAN I. DODDS.
